UNITED STATES PATENT OFFICE.

JAMES WILLIAM McNEIL, OF NEWARK, NEW JERSEY, ASSIGNOR OF ONE-HALF TO JOHN WESLEY ALLISON, OF MORRISBURG, ONTARIO, CANADA.

BARREL.

1,262,222.

Specification of Letters Patent. Patented Apr. 9, 1918.

Application filed October 19, 1918. Serial No. 126,552.

To all whom it may concern:

Be it known that I, JAMES WILLIAM McNEIL, a subject of the King of England, and a resident of Newark, county of Essex, and 5 State of New Jersey, have invented certain new and useful Improvements in Barrels, of which the following is a full, clear, and exact description.

This invention relates more particularly 10 to steel barrels.

One of the principal objects of the invention is to provide a strong and light barrel which will have the general appearance of the ordinary wood barrel and which may 15 have its body formed of a single piece of sheet steel or other metal, thus overcoming many of the objections incident to barrels and their manufacture wherein the body is made up of independent staves.

20 Another object of the invention is to provide a barrel in which the body may have strengthening ribs extending substantially the whole length thereof and other alternately arranged ribs extending part of the 25 length of the body to adapt the body to be strengthened throughout its entire length and also additionally strengthened at the heads or ends of the body.

Other objects of the invention are to provide 30 a barrel wherein the strengthening parts or ribs may be formed in the body and so constructed and arranged that they form a rest or seat for the barrel heads; and to provide means whereby the barrel may be materially strengthened without having deep 35 ribs thereby providing a larger interior surface for packing purposes particularly when objects of some size are intended to be placed within the barrel.

40 A further object of the invention is to provide effective means for securing the barrel heads removably in position.

With these and other objects in view, the invention will be hereinafter more particularly 45 described with reference to the accompanying drawings, which form a part of this application, and will then be pointed out in the claims at the end of the description.

50 In the drawings, Figure 1 is a sectional elevation of one form of barrel embodying the invention.

Fig. 2 is a plan view partly broken away of the construction shown in Fig. 1.

Fig. 3 is a sectional plan view taken on the 55 line III—III of Fig. 1.

Fig. 4 is a fragmentary detail view of the sheet metal blank prior to forming the bulge or bilged part of the barrel and the strengthening ribs of the barrel body. 60

Fig. 5 is an enlarged fragmentary vertical section taken through one of the longer strengthening ribs of the barrel.

Fig. 6 is an enlarged fragmentary vertical section through one of the shorter barrel 65 ribs.

Fig. 7 is a fragmentary plan view of Fig. 5.

Fig. 8 is a fragmentary plan of Fig. 6.

Fig. 9 is a fragmentary section taken on 70 the line IX—IX of Fig. 5, showing one form of means for securing the heads and several parts together.

Fig. 10 is a fragmentary plan view of the outer strengthening band or member at the 75 head.

Fig. 11 is a fragmentary section of the member shown in Fig. 10.

Fig. 12 is a fragmentary plan view showing the head and the retaining band or 80 member for holding the head to the barrel body; and

Fig. 13 is a fragmentary vertical section of the head and holding band or member shown in Fig. 12. 85

The barrel body 10 usually of thin sheet steel is bulged at the center as in an ordinary barrel and along the body are ribs 11 which extend substantially the entire length of the body. Alternately arranged ribs 12 are located between the ribs 11, and said ribs 12 extend from opposite ends of the barrel body to a point somewhat less than midway of said body and may extend substantially one-third thereof or otherwise. The ribs 11 extend transversely inward from the barrel body at the ends to a somewhat greater degree than at the center of the barrel body, while the ribs 12 extend transversely and inward at the outer ends somewhat less than the ribs 11 and taper gradually lengthwise of the body so as to merge or blend into the body. The ribs 11 as well as the ribs 12 are formed by pressing or otherwise by any 95 100 105

suitable means a sheet of steel or other metal to form a bulge or bilged part substantially central thereof, and for this reason the ribs or that part of the sheet utilized to form the 5 ribs taper from the outer edges inward or is greatest at the edges as shown in dotted lines in Fig. 4. The sheet metal is cut away at 13 a part of its length along its edges corresponding to the amount of metal utilized in forming 10 the ribs 11 and the metal sheet is cut away at 14 between the cut-away portions 13 where the shorter ribs 12 are formed. When the barrel body is formed, the metal which is pressed to form the ribs 11 and 12 brings the 15 edges of the metal between the cut-away portions 13 and 14 close together so that the serrated edges of the blank shown in Fig. 4, when the ribs are formed, will result in substantially continuous bands which extend 20 beyond the ends of the ribs. The free ends of the sheet after the ribs are formed are welded together to complete the body or double lapped and riveted or provided with any other suitable fastening means for said 25 ends.

A head 15 substantially cylindrical in form is adapted to rest upon the shoulders 16 of the ribs 11 and 12 formed by the ends of said ribs. There is a head at each end 20 of the barrel body which may be similarly constructed and which may be held to the body 10 in the same way. Each head 15 has an outwardly extending flange 17 which is adapted to be engaged by the turned over 25 end or edge 18 of an annular member or retaining ring 19. The member 19 while the barrel is being assembled is first in the form shown in Fig. 13, and later has its outer portion bent over as shown in Figs. 40 5 and 6, to provide an annular part substantially U-shaped in cross-section which forms an annular channel for the reception of the flange 17 of the head 15. The head holding member 19 may be of steel and may 45 be made of sufficiently light material to permit it to be readily forced or spun over the flange 17 of the head 15 so that the turned over portion 18 may be spread or opened to adapt either or both heads to be removed. 50 The member 19 has pendent portions 20 forming slots or channels 20^a between the same to adapt the portions 20 to fit between the ribs 11 and 12. An annular reinforcing band, member or hoop 21 is arranged on the 55 outside of the barrel body at each end thereof, and between the part 22 of said hoop or band 21 and the member 19 is an annular channel for the reception of the outwardly extending parts 22^a of the barrel body, which 60 latter are formed by the cut-away portions 13 and 14, and which extend beyond the ribs and form a substantially annular flange beyond the ends of the ribs 11 and 12. The member 21 has a skirt portion 23 slightly 65 flared to correspond to the shape of the

barrel body and extends inward along the body a short distance, and at intervals about the barrel body, the skirt portion 23, the parts 22, and the body of the barrel are held together by rivets 24 or otherwise. 70

The head retaining member 19, the member 21, the flange 17 of the barrel head and the parts 22 of the barrel body at each end of the barrel may be secured together by staples 25 or otherwise. These staples have 75 shanks 26 which pass through openings in the several parts and have their inner ends, as 27, bent over so as to hold the staples in place and in such a way that the ends 27 may be spread apart and the staples removed when it is desired to remove either one or both of the heads 15. 80

The body of the barrel at opposite sides of the center may be provided with a strengthening hoop 28. Each hoop 28 may 85 be secured by rivets or otherwise to the barrel body and serves to assist in materially strengthening the barrel and in giving the barrel the appearance of an ordinary 90 barrel.

It will be evident from the foregoing that a simple and efficient barrel is provided which is strong and is easily and cheaply manufactured; that a construction is provided whereby the barrel body may be made 95 of a single sheet and reinforced lengthwise of the barrel body with substantially little or no waste; and that said barrel is effective for holding either granular material or objects of different sizes and is also adapted 100 to permit the same to be arranged for holding liquids or semi-liquids.

Having thus described my invention, I claim as new and desire to secure by Letters 105 Patent:—

1. In combination, a barrel body provided near its end with internal shoulders, the rim of the barrel projecting beyond the shoulders, a head fitted down in the barrel and resting on said shoulders, said head 110 having an annular flange spaced away from said upstanding rim of the barrel, and a ring plate fastened to the interior of the barrel and lying between the rim of the barrel and the flange of the head and having a rim portion projecting beyond the said flange and bent downwardly against its inner face.

2. A metal barrel comprising a body having ribs extending lengthwise thereof, said ribs forming shoulders, said body having substantially annular flanges projecting beyond said shoulders, heads seated upon said shoulders of the ribs, and having outwardly extending annular flanges, a retaining member for each head having parts extending inward between the ribs and having its outer portion adapted to be bent over the flange of the heads so as to form a substantially U-shaped retaining part, an outer 120

- annular member arranged at each end of the barrel body and having a skirt portion extending along a part of said body and having another part located around the projecting part of the barrel body extending beyond the ribs, means for holding the skirt portions and the barrel body together, hoops arranged around the barrel body, and fastenings for securing the heads, the retaining members, the barrel body, and the outer annular members together. 25
5. A metal barrel comprising a body having internal ribs extending lengthwise thereof, said ribs forming shoulders, heads seated upon said shoulders of the ribs and having outwardly extending annular flanges, a retaining member for each head having parts extending inward between the ribs and having its outer portions adapted to be bent over the flanges of the heads so as to form a substantially U-shaped retaining part, an outer annular member arranged at each end of the barrel body, hoops arranged around the barrel body, and means for securing the head and the barrel body together. 30
10. A metal barrel comprising a body having internal ribs extending lengthwise thereof, said ribs forming shoulders, heads seated upon said shoulders of the ribs and having outwardly extending annular flanges, a retaining member for each head having parts extending inward between the ribs and having its outer portions adapted to be bent over the flanges of the heads so as to form a substantially U-shaped retaining part, an outer annular member arranged at each end of the barrel body, hoops arranged around the barrel body, and means for securing the head and the barrel body together. 35
15. A metal barrel comprising a body having internal ribs extending lengthwise thereof, said ribs forming shoulders, heads seated upon said shoulders of the ribs and having outwardly extending annular flanges, a retaining member for each head having parts extending inward between the ribs and having its outer portions adapted to be bent over the flanges of the heads so as to form a substantially U-shaped retaining part, an outer annular member arranged at each end of the barrel body, hoops arranged around the barrel body, and means for securing the head and the barrel body together. 40
20. A metal barrel comprising a body having internal ribs extending lengthwise thereof, said ribs forming shoulders, heads seated upon said shoulders of the ribs and having outwardly extending annular flanges, a retaining member for each head having parts extending inward between the ribs and having its outer portions adapted to be bent over the flanges of the heads so as to form a substantially U-shaped retaining part, an outer annular member arranged at each end of the barrel body, hoops arranged around the barrel body, and means for securing the head and the barrel body together. 45
25. A metal barrel comprising a body having internal ribs extending lengthwise thereof, said ribs forming shoulders, heads seated upon said shoulders of the ribs and having outwardly extending annular flanges, a retaining member for each head having parts extending inward between the ribs and having its outer portions adapted to be bent over the flanges of the heads so as to form a substantially U-shaped retaining part, an outer annular member arranged at each end of the barrel body, hoops arranged around the barrel body, and means for securing the head and the barrel body together. 50

This specification signed this 18th day of 45
October, A. D. 1916.

JAMES WILLIAM McNEIL.
